E. J. Silvius,
ATTORNEY.

UNITED STATES PATENT OFFICE.

CHARLES G. HUNTER, OF LAWRENCE, INDIANA.

WIRE-TWISTING TOOL.

Application filed December 14, 1925. Serial No. 75,361.

This invention relates to a tool that is designed for twisting wires, as when splicing two wires together, or when wrapping a portion of a wire on the main portion thereof to form a loop, especially when building or repairing wire fencing, the invention having reference more particularly to a portable hand-tool that is especially adapted to be used in a small space.

An object is to provide an improved wire-twisting tool that shall be of such construction as to permit manufacture thereof at small cost, and yet be strong and not liable to become impaired because of rough usage or carelessness of inexperienced workmen.

Another object is to provide an improved wire-twisting tool which shall be of such construction as to permit it to be readily carried about and which may be readily and efficiently operated in narrow spaces between fence wires or elsewhere, and which shall have all its parts connected together to guard against loss or misplacement of parts, and shall be durable and economical in use.

With the above mentioned and other objects in view, the invention consists in a wire-twisting tool having novel and improved parts and structural features, and in the combinations and arrangements of parts as hereinafter particularly described and further set forth in the claims appended hereto.

Referring to the drawings,—Figure 1 is a fragmentary side view of a wire fence on a small scale, and the improved tool in connection therewith as illustrative of one of the practical uses of the tool; Fig. 2 is a front view of the improved tool shown as when operating to wrap one portion around another portion of a wire; Fig. 3 is a side view of the tool in which parts thereof are shown in different positions relatively to those in the preceding figure, the lever arm of the tool being broken off; Fig. 4 is a rear view of the tool, a portion of the lever arm being broken off, and Fig. 5 is a fragmentary sectional detail showing the assembly of the principal parts of the tool.

Similar reference characters in the different figures of the drawings indicate corresponding elements or features of construction herein referred to in detail.

In the drawings the numeral 1 indicates a fence post, 2 indicating fencing wires hav-

ing loops 3 connected to the post, each loop being composed of a portion of the fence wire embracing the post and having its end portion secured to the wire by means of a twisted portion 4, the end portion 5 of the wire being twisted or wrapped about the main portion of the wire.

The improved tool comprises a lever arm 6 having a journal box 7 on one end thereof that projects beyond one side of the arm, 65 and a novel twister head operated by means of the arm. The twister head comprises a disk-like plate adapted to constitute a wheel 8 having peripheral ratchet teeth 9, the ratchet wheel having a hub 10 on one side 70 thereof that is journaled in the journal box, the hub having a projection 11 that extends beyond one end of the box, the ratchet wheel being arranged against the opposite end of the box. The ratchet wheel, including its hub, has a slot 12 arranged between two of the ratchet teeth and extending inward to the axis thereof, being longitudinally of the hub, and the wall of the journal box has a gap 13 therein to which the slot may be 80 brought to admit a wire to the axis of the ratchet wheel. The projection 11 is less than half of the diametrical thickness of the hub, preferably being semi-cylindrical, and a collar 14 having guide wings 15 and 16 is arranged on the projection and against the adjacent end of the journal box to retain the hub in the box, the collar being rigidly secured to the projection by means of a bolt 17 and a nut 18 thereon, the bolt being secured transversely in the projection and the nut seated on the outer side of the collar, this permitting removal of the collar. The collar has two curved guide fingers 19 and 20 fixed thereon so as to be on 90 opposite sides respectively of the axis of rotation of the twister head, and the fingers are curved so that they together shall extend in opposite directions across the projection and partially about the axis of rotation, the fingers being separated or twisted so as to admit a wire sidewise between the fingers and to the axis of rotation, in order that the twister head may be readily placed in operative relation on a wire, or 95 removable therefrom.

The face of the ratchet wheel 8 has a pivot stud 21 fixed thereto on one side of the slot 12, being in advance of the slot during rotation of the ratchet wheel, and a lug 22 is 100 110

loosely connected to the stud so as to swing thereon, the lug having a head portion 23 in which is a groove 24 to receive a portion of the wire, the groove being in the side of the head portion 23 that faces towards the pivot stud.

The lever arm 6 is provided with a pivot 25 arranged at a suitable distance from the journal box, and a pawl 26 is loosely connected to the stud and extends towards one edge of the lever arm, being adapted to engage the ratchet teeth 9. The pawl has a controlling arm 27 that extends at approximately right angles relatively to the pawl, and another arm 28 that is approximately in line with the pawl on the opposite side of the pivot and may be carried against a stop pin 29 fixed to the lever arm, to limit the movement of the pawl when swung away from the ratchet wheel. Farther away than the pivot 25 from the ratchet wheel the lever arm 6 is provided with a pivot pin 30, a plunger box 31 is arranged against the arm and has an ear 32 thereon that is connected to the pivot pin, and a plunger 33 is movably guided in the box and normally projected against the arm 27 by means of a coil spring 34 arranged under compression between the plunger and the bottom of the box. The plunger box normally rests against a stop pin 35 secured to the arm 6 and may be swung over into contact with a separate stop pin 36 secured to the arm.

In practical use the pawl 26 is in engagement with the ratchet wheel, and the wheel may be independently rotated in one direction or may be rotated in the same direction by swinging the lever arm to and fro, as will be understood. When the ratchet wheel is stopped so that the slot 12 registers with the gap 13 the tool may be readily applied to a wire or a wire may be carried into the twister head, as occasion may require, the wire being brought under the fingers 19 and 20 by giving the tool a twisting movement relatively to the wire, as will readily be apparent, so that the wire may extend along the axis of rotation of the twister head. One portion of the wire or an end of a wire is brought about another wire and turned sharply over and brought into the groove 24, the lug being swung across the slot 12, as appearing in Fig. 2, and upon operation of the lever arm the twister head is rotated and twists or wraps the wire about another wire and finally secures the portions of the wires together, after which the twister head may be turned so as to bring the slot therein to the gap in the journal box which permits the tool to be disengaged from the wire. By swinging the box 31 over against the stop pin 36 the plunger 33 comes into engagement with the arm 28 and thereby forces the pawl

away and holds it off from the ratchet wheel, permitting a free movement of the wheel.

Having described the invention, what is claimed as new is:—

1. A wire twisting tool including a journal box and a lever arm connected together, the box having a gap in its wall, a twister head comprising a ratchet wheel and a hub connected together and having a longitudinal slot therein, the hub being rotatably arranged in the journal box and having a pair of spirally twisted guides on one end thereof to guide a wire in the slot on the axis of rotation of the hub, a lug pivoted to the ratchet wheel adjacent to one side of the slot and having a head portion to draw a wire portion about the guided wire, and a pawl mounted on the lever arm to engage the ratchet wheel.

2. A wire-twisting tool including a journal box and a lever arm connected together, the box having a gap in its wall, a twister head rotatably connected with the journal box and having a projection eccentrically thereon extending beyond the box, the head having also peripheral teeth and a slot between two of the teeth extending inward to the axis of the head, a guide collar removably secured to the projection adjacent and concentric to the journal box and having two oppositely arranged curved guide fingers rigid thereon and together extending spirally across the projection and about the axis of the head, and a pawl mounted on the lever arm to engage the teeth.

3. A portable hand-operated wire-twisting tool comprising a journal box having a gap in its wall, a lever arm fixed to said box, a twister head rotatably arranged in connection with said box and having a longitudinal slot therein, said head having peripheral teeth, a lug pivoted to the twister head to swing across one end of said slot and having a lateral head portion, two separate guide fingers carried by the twister head and together extending partially about the axis of rotation; said fingers being curved and also twisted in opposite directions, a pawl pivoted to the lever arm to engage said teeth and having two controlling arms, a plunger box pivoted to the lever arm, two stop pins spaced apart and fixed to the lever arm on opposite sides respectively of the plunger box, a coil spring seated in the plunger box, and a plunger movably guided in the plunger box and in contact with the spring, the plunger being movable by the plunger box to either one of the controlling arms to control said pawl.

In testimony whereof, I affix my signature on the 7th day of December, 1925.

CHARLES G. HUNTER.
